RAILWAY BRAKE BEAM MOUNTING

Original Filed Feb. 3, 1943

UNITED STATES PATENT OFFICE

2,460,780

RAILWAY BRAKE BEAM MOUNTING

Edwin G. Busse, Chicago, Ill., assignor to Chicago Railway Equipment Company, Chicago, Ill., a corporation of Illinois

Original application February 3, 1943, Serial No. 474,527. Divided and this application September 28, 1945, Serial No. 619,089

10 Claims. (Cl. 188—212)

1

The invention relates to the supporting and guiding of brake beams from adjacent parts of a railway vehicle, such as a truck side frame, and consists more particularly in a beam structure having a relatively movable element which may be projected into position to oppose the supporting part or retracted to a position to facilitate the assembly and disassembly of the beam and other parts of the vehicle structure.

The main object of the invention is to simplify the supporting and guiding of the beam from the vehicle part and to facilitate the application and removal of the beam and to avoid substantial modification of adjacent vehicle structure or the attachment of moving parts thereto, as shown in Letters Patent Nos. 2,254,513 and 2,254,514 issued to the present inventor September 2, 1941. The present application is a division of an earlier application Serial No. 474,527, filed February 3, 1943, now abandoned, which applicant relies upon for all proper purposes.

In the accompanying drawings illustrating the invention—

Figure 1 is in part a side elevation of a railway four-wheel truck with brake beam supported upon the truck frame, a portion of the frame being broken away and sectioned to more clearly illustrate the construction.

Figure 2 is a top view of one end of the brake beam indicated in Figure 1 and showing portions of the adjacent wheel and truck frame, the same being drawn to an enlarged scale.

Figure 3 is a detail vertical section taken on the line 3—3 of Figure 1.

Figure 4 is a detail section and elevation taken on the line 4—4 of Figure 3.

Figure 5 corresponds generally to Figure 3 but illustrates another form of the invention.

Figure 6 is a detail section and elevation taken on the line 6—6 of Figure 5.

Figure 7 is a top plan view of the structure shown in Figures 5 and 6.

The illustrative truck shown in Figures 1-3 includes wheels 1 mounted on the usual axles (not shown) provided with journal boxes (not shown) which support the truck side frames, each of which comprises a top chord 2, a bottom chord 3 and columns 4 forming a window for the bolster 5 supported on springs 6 seated on the frame lower chord 3. The brakes are applied to the portions of the wheel rims opposite to the bolster and each brake gear includes a truss type brake beam having a compression member 7, a tension member 8 and a brake head 9 including a body

portion having a pocket-forming member 10 for receiving the end of compression member 7, the brake head being seated on the compression member and held to its seat by the nut 11 on the end of the tension member 8 which passes through the pocket end wall 10a.

All of the above-described structure is well known in the art and in itself does not constitute the present invention, which relates to the carrying of the brake beam from the adjacent truck parts 3 each of which is provided with vertically spaced flanges 12 and 13 extending towards the adjacent end of the brake beam but terminating short of the same.

The brake head is provided with transverse apertures 14 above and below the pocket for member 7 and tension member 8, and a U-shaped bracket 23 has vertically spaced legs 24 and 25 slidably received in the lower and upper apertures respectively in the brake head. Preferably the brake head portion 10 includes a lateral flange 26 forming an extended bearing for bracket upper leg 25. A bolt 27 may be passed through flange 26 and bracket leg 25 to hold the bracket in projected position. A supplementary holding means is provided by a bolt 28 passed through lower leg 24 of the bracket and the lower flange of the compression member.

With this arrangement, bracket 23, when projected, supports the end of the beam upon the lower flange 12 on the truck frame and cooperates with the upper flange 13 of the truck frame to guide the beam in its movement to and from the wheels during the application and release of the brakes. When the beam is assembled with the truck, and again when it is to be removed from the truck, bolts 27 and 28 are removed and the bracket retracted to the broken line position indicated at 23a (Figure 3), thus providing for the lifting and dropping of the beam into or out of its functioning position, but it is unnecessary to disassemble any of the beam parts for this purpose.

Figures 5, 6, and 7 illustrate another form of the invention in which the compression member 30 and the tension member 31 of the elongated structure of the beam are formed by splitting a rolled member longitudinally except at its ends. The split portions of the elongated structure are spread to form the tension and compression members of the truss. The end portions are flattened as indicated at 32 to be received within a suitable aperture in the brake head 33 secured to the flattened portion 32 by rivets R. Adjacent the flattened head-mounting end sec-

tion there is provided a rib 34 connecting the compression and tension members and reenforcing the connected portions to resist twisting and spreading forces applied to the beam and tending to cause failure at this point. Transverse passageways 35 are formed in the head at the front and rear of the head-mounting portion 32 of the elongated member and above and below the level of portion 32.

The U-shaped supporting bracket 36 has each of its legs bifurcated, as indicated at 37, with each of its bifurcations received in one of the head passageways 35. The bracket is notched at 38 to receive a cotter 39 seated in a hole in the brake head to hold the bracket in projected or retracted position. When bracket 36 is projected, as shown in full lines in Figures 5 and 7, it is received between flanges 41 and 40 on the truck side frame to support and guide the beam. When cotter 39 is removed, the bracket may be retracted to the broken line position indicated at 36a and the beam may be moved vertically into and out of assembled relations with flanges 41 and 40. Rib 34 is positioned inwardly of the inner end of bracket legs 37 when the bracket is retracted.

Each form of the invention embodies a simple, effective structure for supporting one end of the beam directly from the truck side frame or other adjacent main part of the vehicle in place of the usual swing hanger or in place of members integral with or fixedly assembled with the main portions of the brake beam so that the beam can only be removed by modifying the truck frame or other associated part for this purpose. Ordinarily it will only be necessary to provide the movable bracket element at one end of the beam because dropping that beam end will enable the opposite end to be moved transversely of the vehicle to disengage opposing elements on the beam and frame formed rigid with the same. However, if conditions make such a method of assembly and disassembly impractical, then the movable bracket element may be provided at both ends of the beam.

The details may be varied without departing from the spirit of the invention, and the exclusive use of those modifications coming within the scope of the claims is contemplated.

What is claimed is:

1. In a railway vehicle brake beam, elongated structure, a brake head having a pocket receiving the end of the structure and seating the same, means affixing the head to the structure, there being passageways extending laterally through the head and spaced apart above and below said structure, and a U-shaped bracket with its legs spaced apart vertically and slidably received in said passageways and movable therein to a projected position, in which the bracket may oppose a truck part to support the beam, and into a retracted position, in which the bracket clears the truck part.

2. In a railway vehicle brake beam, elongated structure including a compression member, a brake head having a pocket receiving the end of and seating said member, means fixedly securing the head to the structure, there being passageways extending laterally through the head and spaced apart at the front and rear of said member, and a U-shaped bracket with legs spaced apart transversely of the beam and slidably received in said passageways and movable therethrough to a projected position, in which the bracket may oppose a truck part to support

the beam, and into a retracted position, in which it clears the truck part.

3. In a railway vehicle brake beam, elongated structure comprising converging truss tension and compression members, the ends of said members being reduced in height and merging in a flattened section, a brake head having a transverse recess receiving said section, there being an upright reenforcing rib connecting the 10 converging members and spaced inwardly of the beam from said section, a bracket element extending thru the head and over said flattened section longitudinally of the beam to a projected position, in which it may oppose a cooperating supporting element on a truck main part, and to retracted position in which its outer end is substantially flush with the vertical outer side of the head, to facilitate dropping the beam past said element, and its inner end is adjacent and 20 substantially flush with the top and bottom edges of said rib.

4. A brake beam as described in claim 1 in which the beam is of open truss formation mounting the brake heads at the relative narrow, flattened end portions of the truss, there being a reenforcing brace of deeper section than the flattened end portions extending between the tension and compression members of the beam adjacent to the head mounting portion but 25 spaced inwardly from the bracket when it is in retracted position, and a support-engaging bracket slidable through openings, provided therefor in the head, and inwardly from the end of the beam beyond the inner side of the head 30 and over said flattened end portions up to said brace.

5. In a railway vehicle brake mounting, a brake beam including a break head provided with a plurality of vertically spaced passageways extending 40 through the head longitudinally of the beam, a U-shaped bracket having vertically spaced legs slidable in said passageways to project one end of the bracket outwardly substantially beyond the end of the beam and to retract the bracket to a 45 position in which said bracket end is close to the end of the beam, and a support for the beam comprising a truck frame part with rigid elements positioned above and below said bracket end, when the bracket is projected, and spaced from 50 said bracket when the latter is retracted.

6. In a railway vehicle brake beam, elongated structure, a brake head having a pocket receiving the end of the structure and seating the same, means affixing the head to the structure, and a U-shaped bracket with its legs spaced apart vertically and slidably mounted on the elongated structure and movable thereon to a position in which one end of the bracket is projected beyond the end of the beam and may cooperate with a 55 member on a truck frame part to support the beam, and the bracket may be retracted to a position in which said bracket end is close to the 60 brake head to provide the beam clearing said truck frame part to apply and remove the beam from the truck.

7. In a railway vehicle brake beam, elongated structure including a compression member, a 65 brake head having a pocket receiving the end of and seating said member, means fixedly securing the head to the structure, and a U-shaped bracket with legs spaced apart transversely of the beam and slidably on said elongated structure to a position in which one end of the bracket is projecting outwardly beyond the end of the compression member, in which it may oppose a truck

part to support the beam, and into a retracted position, in which the bracket clears said truck part.

8. In a railway vehicle brake beam, elongated structure, a brake head having a pocket receiving the end of the structure and seating the same, means affixing the head to the structure, there being a pair of passageways extending laterally thru the head above said structure and spaced apart at the front and rear of said structure, there being another pair of passageways extending laterally thru the head below said structure and spaced apart at the front and rear of said structure, and a U-shaped bracket with its legs spaced apart vertically and each bifurcated, with each bifurcation slidably received in one of said passageways, the bracket being movable to a projected position, in which it may oppose the truck part to support the beam, and into a retracted position, in which the bracket clears such truck part.

9. In a railway vehicle brake beam, elongated structure, a brake head having a pocket receiving the end of the structure and seating the same, means affixing the head of the structure, and a U-shaped bracket with its legs spaced apart vertically, each leg being bifurcated with the bifurcations spaced apart forwardly and rearwardly of said structure, the bracket being slidably mounted on the elongated structure and being movable thereon to a position in which one end of the bracket is projected beyond the end of the beam

and may cooperate with a member on a truck frame part to support the beam, and the bracket may be retracted to a position in which said bracket end is close to the brake head to provide for the beam clearing said truck frame part to apply and remove the beam from the truck.

10. In a railway vehicle brake beam, elongated structure, a brake head structure having a pocket receiving end of the elongated structure and seating the same, means affixing the structures to each other, there being a passageway extending laterally through the head structure, and a bracket slidably received in said passageway and movable therein to a projected position, in which the bracket may oppose a truck part to support the beam, and to a retracted position, in which the bracket clears the truck part, there being bracket-engaging surfaces on at least one of said structures extending inwardly from the end of the beam beyond the inner side of the head structure.
